W. HIBY

CONSTRUCTION OF VERTICAL CHAMBER OVENS

Filed Dec. 17, 1920

Inventor: Walther Hiby
by W. J. Bissell
Attorney

UNITED STATES PATENT OFFICE.

WALTHER HIBY, OF SCHEVENINGEN, NETHERLANDS, ASSIGNOR TO JOHAN CHRIS-TIAAN BARON VAN HAERSOLTE VAN HAERST, OF DRIEBERGEN, THE NETHERLANDS.

CONSTRUCTION OF VERTICAL-CHAMBER OVENS.

Application filed December 17, 1920. Serial No. 431,469.

To all whom it may concern:

Be it known that I, WALTHER HIBY, a subject of the German Republic, residing at Scheveningen, Zeekant 55, the Netherlands, have invented certain new and useful Improvements in the Construction of Vertical-Chamber Ovens, of which the following is a specification.

The even heating of known vertical chamber ovens is very difficult, because the right distribution of heating gas and air for combustion is rarely obtained.

In the present invention the use of horizontal flues in the heating walls is abandoned and the combustion as well as the off-take of the burnt-gases is solely done in vertical flues. Only the long sides of the vertical chambers are heated. As shown on the drawing heating gas and air for combustion are led—separated one from the other—to the vertical heating flues by means of horizontal canals, which are situated in the lower part of the heating wall. The regulation of heating gas and air is preferably done by means of dampers, arranged at the upper ends of the flues. In case all adjoining vertical flues would be heated directly and the burnt-gases be taken off from the upper part of the oven at one place only and led to the heat-exchangers (recuperators), the even heating over the total height of the chamber would be impossible, as the temperature in the long heating flues cannot be the same in their whole length. If on the other hand alternate burnt-gas flues are built between the heating flues proper, then an exchange of heat occurs. The burnt-gas takes heat from the hottest parts of the adjoining directly heated flues and carries it to lesser heated parts of the chamber walls and an even heating is assured.

Figure 1 is a vertical section of the ovens passing thru a heating wall on line 1—1 of Fig. 2.

Fig. 2 is a transverse section thru heating walls and oven chambers on line 2—2 of Fig. 1.

Fig. 3 is a horizontal section taken respectively on lines 3—3, 4—4, 5—5 and 6—6 of Fig. 1.

The invention is shown on the accompanying drawing in Figures 1, 2 and 3, *a* are

the vertical coking chambers with the interposed heating walls *b*. In the walls *b* are situated the directly heated flues *c*, which alternate with the double flues *d* for the off-take of the burnt gases. The heating gas is led to the single flues *c* from pipe *e* by means of a branch pipe *f* and the horizontal canal *g*, from which it discharges through openings *h* into each flue *c*. The air for combustion enters the heat-exchangers (recuperators) through openings *i* into chambers *k*, passes through the same in upward direction in counter-current to the offheat, is collected in the canal *l*, goes sideways to the heating wall, discharges through openings *m* and meets in two streams the heating gas, streaming from openings *h*.

The flues *c* are, as described, heated directly, while the burnt-gas goes downward through the double flues *d*, to be collected in the canals *n*; it goes sideways to the heat-exchangers, passes downward in the latter in double flues *o* in counter-current to the rising air and is led through opening *p*, regulated by a sliding damper *r*, to the chimney flues *q*.

The even heating of all flues *c* is effected by adjusting the gas pressure in the pipe *e* and canal *g* and by regulating the upper outlet openings of flues *c* by means of dampers *s*. The burnt-gas is evenly distributed to the flues *o* of the heat-exchanger by means of regulating-dampers *t*.

Having now described my invention what I claim as new and desire to secure by Letters Patent is:

1. In a vertical chamber oven provided with flat sided vertical oven chambers with filling openings at the top and discharge openings beneath the oven chambers, the combination of vertical heating walls outside of said oven chambers and extending lengthwise of the longitudinal axes of said chambers and on each of the long sides thereof, vertical heating flues in the heating walls, means for supplying gas and air for combustion to said heating flues, said means being located in the lower part of the heating walls, a plurality of vertical flues for the burnt gases arranged adjacent to the heating flues, the tops of the heating flues and the inlet ends of the burnt gas flues of a

heating wall communicating with each other, the discharge ports of the burnt gas flues located in the lower parts of the chamber walls so as to return the burnt gases to said parts; thereby securing an exchange of heat between the heating flues and the burnt gas flues.

2. In a vertical chamber oven the combination of vertical heating walls outside of the oven chambers and extending lengthwise of the longitudinal axes of said chambers and on each side thereof, vertical heating flues in the heating walls, horizontal canals arranged in the lower part of said heating walls and leading to said flues, means for supplying gas and air for combustion separately to said canals, a plurality of vertical flues for the burnt gases arranged between the heating flues, the tops of the heating flues and the inlet ends of the burnt gas flues of a heating wall communicating with each other, the discharge ports of the burnt gas flues located in the lower parts of the chamber walls so as to return the burnt gases to said parts, thereby securing an exchange of heat between the heating flues and the burnt gas flues.

3. In a vertical chamber oven the combination of vertical heating walls, outside of the oven chambers and extending lengthwise of the longitudinal axes of said chambers and on each side thereof, vertical heating flues in the heating walls, horizontal canals arranged in the lower part of said heating walls and leading to said flues, means for supplying gas and air for combustion separately to said canals, a plurality of vertical flues for the burnt gases built between the heating flues and arranged alternately therewith, the discharge ports of the said burnt gas flues being located in the lower parts of the chamber walls so as to return the burnt gases to said parts; thereby securing an exchange of heat between the heating flues and the burnt gas flues.

4. In a vertical chamber oven the combination of vertical heating walls outside of the oven chambers and extending lengthwise of the longitudinal axes of said chambers and on each side thereof, vertical heating flues in the heating walls, horizontal canals arranged in the lower part of said heating walls and leading to said flues, means for supplying gas and air for combustion separately to said canals, a plurality of vertical flues for the burnt gases built between the heating flues and arranged alternately therewith, there being two burnt gas flues for each heating flue, the discharge ports of the said burnt gas flues being located in the lower parts of the chamber walls so as to return the burnt gases to said parts; thereby securing an exchange of heat between the heating flues and the burnt gas

flues, and horizontal canals for the burnt gases, adjacent to the air canals leading to the heating flues.

5. In a vertical chamber oven the combination of heating walls for opposite sides of the oven chambers, vertical heating flues alternating with vertical burnt gas flues in said walls, horizontal canals arranged in the lower part of said heating walls and arranged in each of said heating walls communicating respectively with said vertical heating flues, for supplying gas and air to said heating flues.

6. In a vertical chamber oven the combination of heating walls for opposite sides of the oven chambers, vertical heating flues alternating with vertical burnt gas flues in each of said walls, horizontal air channels and horizontal gas channels arranged in each of said heating walls communicating respectively with said vertical heating flues, for supplying gas and air to said heating flues, a horizontal channel in each of said heating walls communicating with the burnt gas flues, the horizontal air channels for each heating wall lying between the horizontal burnt gas channels of the said heating wall.

7. In a vertical chamber oven the combination of heating walls for opposite sides of the oven chambers, vertical heating flues alternating with vertical burnt gas flues in each of said walls, horizontal channels arranged in each of said heating walls communicating with said vertical heating flues, for supplying gas and air to said heating flues, said horizontal channels extending within the lower part of each heating wall along the lower ends of the vertical flues at right angles thereto and burnt gas channels communicating with the lower parts of the burnt gas flues for discharging the burnt gases therefrom.

8. In a vertical chamber oven the combination of heating walls for opposite sides of the oven chambers, vertical combustion flues alternating with vertical burnt gas flues in each of said walls, said heating flues communicating with the burnt gas flues, means for supplying gas to the lower part of the combustion flues, means for pre-heating the air arranged at the rear of the oven battery, channels connecting the preheater with the lower part of the vertical heating flues, and waste channels for the burnt gases connecting with the lower part of the vertical burnt gas flues.

9. In a vertical chamber oven the combination of heating walls for opposite sides of the oven chambers, vertical combustion flues alternating with vertical burnt gas flues in each of said walls, said heating flues communicating with the burnt gas flues, means for supplying gas to the combustion flues, means for preheating the air arranged

at the rear of the oven battery, said means comprising a recuperator for preheating the air, said recuperator containing passageways for receiving the waste heat, horizontal channels connecting the recuperator with the lower part of the vertical heating flues and horizontal channels connecting the

lower part of the vertical burnt gas flues with the waste heat passageways of the pre-heater.

In testimony whereof I affix my signature.

10

WALTHER HIBY.
